his attorney

UNITED STATES PATENT OFFICE.

OLIVER WILBURN THOMAS, OF PANA, ILLINOIS.

WRENCH.

1,287,798.

Specification of Letters Patent. Patented Dec. 17, 1918.

Application filed January 23, 1918. Serial No. 213,412.

To all whom it may concern:

Be it known that I, OLIVER W. THOMAS, a citizen of the United States, and a resident of Pana, in the county of Christian and State of Illinois, have invented new and useful Improvements in Wrenches, of which the following is a specification.

This invention relates to wrenches and has particular reference to the class of wrenches of the cross-handle type.

An important object of the invention is to provide in a device of the above mentioned character a means whereby the greatest possible gripping effect upon the object desired to be operated upon may be attained.

A further object of the invention is to provide in a device of the above mentioned character a means whereby various adjustments of the jaws with respect to each other may be easily and quickly made.

A further object of the invention is to provide a device so constructed as to readily permit the attachment of a wire cutting device to the same without materially altering or changing any of the essential elements.

A further object is to provide a device of the above mentioned character which is strong, durable, cheap to manufacture and reliable in operation.

Other objects and advantages will be apparent during the course of the following description.

In the drawings, forming a part of this specification and in which like numerals are employed to designate like parts throughout the same,

Fig. 1 is a side elevation of the device embodying my invention, the same being shown partly in section,

Fig. 2 is a vertical transverse section of Fig. 1 taken on line 2-2,

Fig. 3 is a fragmentary elevation of the device, the same being shown partly in section,

Fig. 4 is a side elevation of the device showing the attachment of a wire cutter thereto,

Fig. 5 is a side elevation of the same showing the jaws in a closed position with respect to each other, and,

Fig. 6 is a fragmentary edge view of the same.

In the drawings, attention being called to Figs. 1 to 3 inclusive, wherein is shown the preferred form of my invention the numeral

10 indicates an elongated handle portion, one end of which is machined to form a screw-driver as shown at 11, while the other end is provided with an angularly disposed head or jaw 12, one edge or face of which is provided with a plurality of gripping teeth as shown at 13. The handle 10 is provided with a plurality of openings 14, each of which are connected one with the other by means of walls or passages 15, the width of each being slightly less than the diametrical length of the openings 14. A second handle 16 provided with depending flanges 17 is secured to the first mentioned handle 10 by means of a screw-threaded pivot 18 one end of which is slightly reduced and provided with screw-threads as shown at 19 while upon the other end there is disposed an enlarged head 20. This pivot 18 is passed through an opening 21 provided by one of the flanges 17, through the opening 14 carried by the handle 10, thus bringing the screw-threaded portion 19 into engagement with a screw-threaded opening 22 carried by the other flange 17 as shown. It will be noted that each side of the pivot 18 is slightly flattened as shown at 23 and that the faces 23 of the pivot 18 assume a right-angle position with respect to the handle 10 when the enlarged head 20 is brought firmly into engagement with the adjacent flange 17 as shown.

In forming the jaw 24 I utilize the enlarged portions of the flanges 17 as shown at 25 by securing therebetween a block 26, the face of which is serrated or provided with teeth as shown at 27. I have shown this block as being secured between the enlarged portions 25 of the flanges 17 by means of rivets 28 or the like but I wish it understood however that this might be retained therebetween by welding if so desired.

In considering the modified form of my invention as shown in Figs. 4 to 6 inclusive, it will be noted that the general structure of the same is identical with that disclosed in Figs. 1 to 3 inclusive, and hereinbefore described except, however, I have dispensed with all of the openings 14 except one and have applied to the handle 10 a wire-cutting device indicated as a whole by the numeral 29, which device comprises a reciprocatory cutting member 30, one end of which is beveled as shown at 31. This reciprocatory member is slidably carried within a pair of yokes 32 secured to the handle 10 as shown.

In order to retain the member 30 normally in the position shown in Fig. 4 there is provided a spring 33, one end of which is connected to the handle 10 as shown, while the 5 other end is adapted to engage the reciprocating member. In proximity to the bevel-cutting edge 31 there is provided a recess 34, one edge of which is beveled to form a cutting edge 35 adapted to co-act with the 10 cutting edge 31 carried by the reciprocating member 30.

In use, the operation of the preferred embodiment of my invention is as follows: The 15 object to be operated upon, I have shown in this instance a pipe P, is inserted between the faces of the jaws 12 and 24 of the device and is clamped therein as will readily be understood when considering the disclosure as shown in Fig. 1. Should it be desired to vary the distance between the two 20 jaws this may be done by rotating the pivot 18 to such a position as will bring the faces 23, carried thereby, in alinement with the passages 15 whereupon the pivot 18 may be 25 passed longitudinally with respect to the handle 10 from one opening to the other. When this pivot has been passed into the desired opening the same may be rotated to the position shown in Fig. 1, the pivot when 30 in this position it will be understood will be retained within the opening carrying the same regardless of any position the handle 16 may maintain with respect to the handle 10.

35 In considering the operation of the modified form of the device as shown in Figs. 3 to 6 inclusive, I need only describe the op-

eration of the wire-cutting device 29, which operation is as follows: Should it be desired to sever a wire, the same is inserted into the 40 recess 34 and the handle 16 is moved to the position shown in Fig. 5, whereupon the reciprocating member 30 is moved to the position shown in Fig. 5, thereby severing the 45 wire carried within the recess 34 as is apparent from the drawings taken in connection with the specification of the same.

It is to be understood that various changes in the shape, size and arrangement of parts 50 may be resorted to without departing from the spirit of my invention or the scope of the subjoined claim.

Having thus described my invention, what I claim as new and desire to secure and protect by Letters Patent of the United States, is: 55

The combination with a wrench having a pair of pivotally connected members each having a wrench jaw, one of said members having a recess formed therein to provide a cutting edge, the other of said members being provided with a cam face formed on a continuation of the face of the jaw thereof; of a reciprocating member provided with a cutting edge and having sliding engagement with said cam face whereby the reciprocating member is moved with respect to said recess upon the actuation of one of said members to produce a coöperating shearing action between the two cutting edges, a plurality of yokes for guiding said reciprocating element, and spring tension means for retaining the reciprocating member normally in a retracted position. 60 65 70

OLIVER WILBURN THOMAS.
